UNITED STATES PATENT OFFICE

ANTHONY F. SCHWENDNER, OF ESSINGTON, PENNSYLVANIA, ASSIGNOR TO WESTINGHOUSE ELECTRIC & MANUFACTURING COMPANY, A CORPORATION OF PENNSYLVANIA

THROTTLE-VALVE-OPERATING MECHANISM

Application filed April 26, 1928, Serial No. 273,029. Renewed January 15, 1930.

My invention relates to a valve-operating mechanism, more particularly to a mechanism for operating the throttle valve of a prime mover, and it has for its object to provide a mechanism of the character designated having power means under manual control for moving the throttle valve in both opening and closing directions.

The present invention is an improvement upon the throttle valve operating mechanism described and claimed in my Patent No. 1,729,458, issued September 24, 1929, wherein a piston connected to the throttle valve is biased to closed position by a spring and actuated in opening direction by fluid pressure. The throttle valve may be closed by releasing the fluid pressure, permitting the spring to close the valve. The arrangement is such, however, that when the fluid pressure is once released, it cannot be restored until the throttle valve has been completely closed. Therefore, to partly close the throttle valve it is necessary to apply manual force to overcome the fluid pressure on the operating piston. This construction has been found satisfactory on throttle valves of moderate sizes, but for larger valves the manual force required becomes considerable.

In accordance with the present invention, I provide power means for moving the throttle valve in either direction to any desired extent. More specifically, I provide means whereby, when it is desired to move the valve in closing direction, fluid pressure is released until the valve reaches the desired position, at which it is then retained. A control member is provided which controls the power means to move the piston to follow the control member. Means for effecting complete closing independently of the position of the control member are also provided.

Apparatus exemplifying my invention is illustrated in the accompanying drawings, in which:

Fig. 1 is a diagrammatic view showing the operating mechanism in combination with the other parts of the prime mover with which it cooperates;

Fig. 2 is a vertical section of the improved throttle valve operating mechanism;

Fig. 3 is a detail view, as seen in plan from the line III—III of Fig. 2, and

Fig. 4 is a fragmentary view showing a detail of Fig. 2 on an enlarged scale.

Referring to the drawings more in detail, I show a throttle valve 10, which is operated by the mechanism indicated at 11, and which controls the supply of motive fluid to a prime mover, of which is shown only a fragment of the shaft at 12. Fluid pressure is supplied to the operating mechanism 11 by a centrifugal pump 13, having an impeller 14 mounted directly on the shaft 12. Fluid discharged under pressure from the pump 13 is conveyed by a conduit 15 to the operating mechanism 11, said fluid flowing through a restricted orifice 16 interposed in the conduit 15.

A branch conduit 15' communicates with an auxiliary source of fluid pressure, such as a pump 13'. Check valves 71 and 72 are provided in the conduits 15 and 15', respectively, to prevent loss of pressure from one pump to the other.

An auto-stop governor, indicated at 17, includes a valve 18 communicating with the conduit 15 at a point between the orifice 16 and the operating mechanism 11. A lever 19, pivoted at 20, is retained in position to hold the valve 18 closed by contact with one arm of the bell-crank lever 21. A plunger 22, carried by the shaft 12, is adapted to move outwardly upon a predetermined overspeed of the shaft, and to strike the other arm of the bell-crank lever, moving the first arm out of engagement with the lever 19. The valve 18 is then free to open and release the fluid pressure in the communicating part of the conduit 15.

Referring now to Fig. 2, the valve-operating mechanism 11 includes a cylinder 31 and a piston 32 operating therein. The piston 32 is formed with an opening 33 at the center thereof, and is connected to the rod 34 through the bushing 35, which is made integral with the piston through webs 36 and in which bushing the rod 34 is secured.

Disposed on the piston 32 above the opening 33 is a housing member 37 secured to the piston in any suitable manner as by screws 100

38. A row of openings 39 are disposed around the circumference of the member 37 near the lower end thereof, and the member 37 is also provided with a valve seat 40 at the opening 38. A valve member 41 includes a sleeve part 42, which has a sliding fit in the housing member 37. The valve member 41 also has a valve part 43 which is adapted to seat on the valve seat 40 upon upward movement of the valve member 41.

10 The valve member 41 is biased upwardly to close the valve 43 by a compression spring 44, which may be disposed between the lower end of the valve member 41 and a part of the piston such as the webs 36. The valve member 41 is also provided with stops 45 extending downwardly from the valve part 43 and adapted to contact with the bushing 35 to limit downward movement of the valve member:

15 The valve part 43 of the valve member 41 is also provided with a valve seat 46 on the inner side thereof. Disposed within the sleeve part 42 is a second vertically slideable valve 47 adapted to seat on the valve seat 46. The sleeve part 42 is provided with a row of openings 48 at the lower end thereof whereby fluid passing by the valve seat 46 may flow through the openings 48 and 39.

20 The valve member 47 is actuated by a stem 51, which may be termed the control member of the operating mechanism. The stem 51 is adapted to abut the valve member 47 to move it in a downward direction or to hold it against upward movement. The valve member 47 includes a ball bearing 52 for receiving the downward thrust without friction due to rotary motion of the stem 51.

25 The screw-threaded stem 51 engages a screw-threaded bushing 52, secured in an opening 53 in the upper end wall of the cylinder 31, and held against rotation by a set screw 54. The stem 51, above the threaded portion, is flattened on opposite sides as indicated at 55. An operating member, here disclosed as a hood or cap 56 fitting over the upper end of the cylinder, has a small member 57 at the top thereof, which has an opening 58 through which the stem 51 extends. Fig. 3 shows the member 57 in plan. The opening 58 has flat sides engaging the flat sides of the stem 51, whereby the rotary motion of the operating member 56 is transmitted to the stem 51, and the stem 51 is free to move vertically through the member 56. The operating member 56 is preferably provided with handles 59 for manually operating the same.

30 Compression springs 61 and 62 are interposed between the upper end wall of the cylinder 31 and the piston 32, the piston 32 being provided with a spring-holding member 63, mounted on the flange of the housing member 37 in the manner of a ball and socket joint. The lower end of the cylinder com-

municates with the conduit 15 through a passage 64 formed in the lower end wall of the cylinder. The upper end of the cylinder communicates through a passage 65 with a drain conduit 66, through which fluid released through the opening 33 may be discharged.

35 The operation of the above described apparatus is as follows:

40 With the piston in the position shown in Fig. 2, the throttle valve is closed, and the prime mover is shut down. Suppose now that it is desired to start operation of the prime mover. The auto-stop governor 17 is set as shown in Fig. 1, with the valve 18 closed. Fluid pressure is conveyed to the conduit 15 from the auxiliary pump 13 through the conduit 15', and supplied to the lower end of the cylinder 31. The fluid pressure acts on the lower side of the piston in opposition to the force of the springs and begins to raise the piston. The valve 43, however, is held against upward movement by abutment with the valve 47, which, in turn, is held against upward movement by abutment with the stem or control member 51. The valve seat 40 therefore leaves the valve 43, thereby providing an opening through which the fluid pressure is released.

45 To open the throttle valve, therefore, the stem 51 is raised by rotating the operating member 56, whereupon the fluid pressure in the lower end of the cylinder forces the valve member 47 upwardly against the stem, and the fluid pressure and the spring 33 force the valve member 41 upwardly against the valve member 47. The valve part 43 moves against the valve seat 40, cutting off the escape of fluid pressure, and the fluid pressure then raises the piston 32 as the stem 51 is raised.

50 Should the stem 51 be raised faster than the restricted flow of fluid pressure to the cylinder can raise the piston 32, the valve 47 leaves the valve seat 46, permitting the fluid pressure to escape through the valve 46 and through the openings 48 and 39. The springs 61 and 62 then are effective to move the piston 32 downwardly to shut the throttle valve. Since the valve 47 can be moved to closed position only by abutment of the stem 51, it is necessary to lower the stem to a position corresponding to closed position of the throttle valve, and then again to raise the stem 51.

55 Assume now that the throttle valve is open and the prime mover exceeds a predetermined overspeed, which is usually set at about 10% above the normal operating speed. The auto-stop governor releases the fluid pressure in the conduit 15, as described above, thereby releasing the fluid pressure in the lower end of the cylinder 31. Springs 61 and 62, therefore, become effective to move the piston 32 downwardly to close the

throttle valve. As soon as the piston 32 has moved downwardly a short distance, sufficient that the stem 51 does not hold the valve member 47 on the seat 46, the fluid pressure in the lower end of the cylinder 31 escapes through the valve 46, and the openings 48 and 39. In view of the short, direct path thus provided for the escape of the fluid, a rapid closing of the throttle valve by the springs 61 and 62 is permitted. It will be noted that it is not necessary to discharge all the fluid from the cylinder 31 through the relatively long conduit 15, only sufficient flow to open the valve 46 being necessary through said conduit. The throttle valve cannot again be opened until the stem 51 is lowered and slowly raised.

Assume again that the throttle valve is open and that it is desired to close the throttle valve under manual control, either partly or completely. The stem 51 is lowered, which moves the valve member 43 off its seat 40. An opening is therefore provided through which fluid pressure is released, permitting the springs to lower the piston until the valve opening is closed or, more exactly, diminished to an extent sufficient to permit only the escape of the restricted flow of fluid into the cylinder. It will thus be seen that by lowering the stem 51, the piston 32 is caused to follow the movement of the stem.

When the turbine is shut down, it is desirable that the throttle valve be held against its seat by a positive force. The stem 51 is, therefore, lowered beyond the position shown in the drawing, until the stops 45 on the valve member 41 engage the bushing 35. It will thus be seen that there is then a positive force from the stem 51 transmitted through the valve member 47, the valve member 41, the bushing 35 and the rod 34 to the throttle valve.

In order that the operator may know definitely, when raising the stem 51, that the piston 32 is following the stem, I provide an indicator 73. This indicator consists of a thin rod disposed in an opening 74 extending longitudinally through the stem 51, and having an indicating button 75 in the enlarged upper end of the opening 74.

When the stem 51 abuts the valve member 47, the lower end of the indicator 73 also rests on the valve member 47 and raises the button 75, which projects out from the stem 51 to provide a visual indication that the stem is abutting the valve member, and that the piston 32 is following the stem, if the latter is being raised. When, however, the stem 51 and the valve member 47 separate, the indicator falls by gravity and the indicating button 75 disappears within the stem 51. The operator then knows that there is no contact between the stem 51 and the valve member 47, and that the throttle valve must, therefore, be on its seat.

From the above description it will be seen that I have provided a throttle valve wherein there is provided power means for closing the throttle valve under full manual control as well as for opening the throttle valve. At the same time the safeguard of retaining the throttle valve shut until the control member is brought to closed position is retained.

While I have shown my invention in but one form, it will be obvious to those skilled in the art, that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:—

1. The combination with a throttle valve, of a motor device for operating the same in both opening and closing directions, manually operated means for controlling the motor device to provide open, closed or intermediate position of the throttle valve, and trip means for controlling said motor device to effect complete closing of the throttle valve.

2. The combination with a throttle valve, of a motor device for operating the same in both opening and closing directions, manually operated means for controlling the motor device to provide open, closed or intermediate position of the throttle valve, and trip means superseding the manually operated means for controlling said motor device to effect complete closing of the throttle valve.

3. The combination with a throttle valve, of a manually-actuated control means, a motor device for operating the throttle valve in both opening and closing directions under control of said means for the full travel of the motor device, trip means superseding said manually-actuated control means for controlling said motor device to effect complete closing of the throttle valve, and means effective upon operation of the trip means for rendering the motor device ineffective to open the valve until said control means is brought to position corresponding to closed position of the throttle valve.

4. The combination with a throttle valve, of operating mechanism therefor comprising a manually operated control member adjustable to various positions corresponding to closed, open and intermediate positions of the throttle valve, power means for moving the throttle valve in both opening and closing directions to the position corresponding to the position of the control member, and other means for effecting power actuated closing of said throttle valve independently of the position of said control member.

5. The combination defined in claim 4 and means effective upon operation of said last-mentioned means for retaining the throttle

valve closed until said control member is brought to the position corresponding to closed position of the throttle valve.

6. In a throttle valve operating mechanism, the combination of a cylinder, a piston operating therein and connected to the throttle valve, a control member movable to various positions corresponding to various positions of the piston intermediate the limits of its travel, means for applying force to said piston to follow movements of said control member in both opening and closing directions, and means for effecting complete closing of the throttle valve independently of the position of said control member.

7. The combination with a throttle valve, of means for operating the same comprising a cylinder, a piston operating therein and connected to the throttle valve, means biasing the throttle valve to closed position, means for supplying fluid pressure to the cylinder to open the valve, trip means for releasing said pressure, and other means for releasing said pressure to move the throttle valve in closing direction to any desired extent.

8. The combination with a throttle valve, of means for operating the same comprising a cylinder, a piston operating therein and connected to the throttle valve, means biasing the throttle valve to closed position, means for supplying fluid pressure to the cylinder to open the valve, trip means for releasing said pressure, and other means for closing the throttle valve by releasing said fluid pressure, said other means controlling the extent of the closing movement of the throttle valve.

9. The combination with a throttle valve, of means for operating the same comprising a fluid pressure operated member connected thereto, means biasing said throttle valve to closed position, means for applying fluid pressure to said member in opposition to said bias for operating the same, means for controlling said fluid pressure to open and close the valve, tripping means adapted to release said fluid pressure, and further means permitting release of said fluid pressure when said tripping means operates.

10. In a throttle valve operating mechanism, the combination of a cylinder, a piston operating therein and connected to the throttle valve, a control member, means for applying force to said piston to follow movements of said control member in both opening and closing directions, means for effecting complete closing of the throttle valve independently of the position of said control member, and means preventing opening of the throttle valve upon operation of the last-mentioned means until said control member is brought to position for closing the throttle valve.

11. In a throttle-valve operating mechanism, the combination of a cylinder, a piston

operating therein and connected to the throttle valve, said piston being formed with an opening therethrough and a valve seat surrounding said opening, a valve member carried by said piston and cooperating with said valve seat, means biasing said valve member to closed position, said valve member being formed with an opening therethrough and a valve seat surrounding the opening, a second valve member carried by said piston and cooperating with the valve seat of the first valve member, and a stem extending from the cylinder and adapted to actuate the second valve member, and also the first valve member through the second valve member.

12. The combination with a throttle valve, of an operating mechanism therefor comprising a cylinder, a piston operating in said cylinder and connected to the throttle valve, said piston having an opening therethrough, an axially movable valve member for closing said opening upon movement in the direction of opening of said throttle valve, said valve member also having an opening therethrough, a second valve member for closing said last-mentioned opening upon movement in the direction of closing the throttle valve, said second valve member being adapted to abut said first valve member upon closing the opening therein and to move the same in opening direction upon further movement, and a control member for actuating the second member in closing direction by abutment therewith.

13. The combination with a valve, of an operating mechanism therefor comprising a cylinder, a piston operating therein and connected to the valve, a spring biasing said piston in one direction, means for admitting a continuous restricted flow of fluid under pressure to said cylinder to act on said piston in opposition to the spring force thereon, a control member manually adjustable to various positions corresponding to different positions of the valve, means biased to closed position by said spring for providing a restricted outlet of fluid from said cylinder, means operated by the control member when the latter is moved in the direction of spring force on the piston to relieve the fluid pressure and permit the spring to cause the piston to follow the movement of the control member, and means operated when the control member is moved in the other direction to cut off outflow of fluid to cause the piston to follow the control member.

14. In an operating mechanism for the throttle valve of a prime mover, the combination of a cylinder, a piston operating therein and connected to the throttle valve, a control member movable to various positions corresponding to different positions of the piston, means for applying force to said piston to move the same to an extent determined by the position of said control member in

both opening and closing directions, and means responsive to an abnormal operating condition of said prime mover for effecting complete closing of the throttle valve independently of the position of said control member.

15. In an operating mechanism for a valve, the combination of a cylinder, a piston operating therein and connected to the valve, a spring biasing the piston to close the valve, said piston having an opening therethrough and a valve adapted to close said opening, a stem extending through the cylinder and adapted to abut against the valve for closing the opening, and means for indicating when said stem abuts the valve member.

16. In an operating mechanism for a valve, the combination of a cylinder, a piston operating therein and connected to the valve, a spring biasing the piston to close the valve, said piston having an opening therethrough and a valve adapted to close said opening, a stem extending through the cylinder and adapted to abut against the valve for closing the opening, said stem having an opening therethrough extending to the valve, and an indicating member extending through said opening in the stem from the valve to the outer end of the stem and adapted to move outwardly when the stem abuts the valve to provide a visual indication of said abutment.

17. The combination with a throttle valve, of an operating mechanism therefor comprising a motor device for moving the throttle valve in either opening or closing direction, means for controlling said motor device to provide any desired extent of opening of the throttle valve, means adapted to supersede said control means and effect complete closing of the throttle valve, and means whereby the throttle valve cannot be opened after operation of the second-mentioned means until the first-mentioned means is operated.

18. In an operating mechanism for a valve, the combination of a piston connected to the valve for operating the same, a cylinder in which the piston operates, means biasing the valve in closing direction, means for admitting fluid pressure to the cylinder to act on the piston in valve opening direction, a control member movable to various positions corresponding to open, closed and intermediate positions of the valve, valve means controlling the application of fluid pressure to the piston for causing movement thereof in either opening or closing direction to the position thereof corresponding to the position of the control member, and means effective when the valve is closed to prevent opening thereof until the control member is moved to the position thereof corresponding to closed position of the valve.

19. In an operating mechanism for a valve, the combination of a piston connected to the valve for operating the same, a cylinder in

which the piston operates, means biasing the valve in closing direction, means for admitting fluid pressure to the cylinder to act on the piston in valve opening direction, a control member movable to various positions corresponding to open, closed and intermediate positions of the valve, valve means controlling the application of fluid pressure to the piston for causing movement thereof in either opening or closing direction to the position thereof corresponding to the position of the control member, and means effective when the valve is closed to prevent the application of fluid pressure to the piston for opening the valve until the control member is moved to the position thereof corresponding to closed position of the valve.

20. The combination with a valve, of means for operating the same comprising a motor device adapted to move the valve both in opening and in closing directions, a control member movable to various positions corresponding to open, closed and intermediate positions of the valve, means operative upon movement of the control member to move the valve in either direction to its corresponding position, and means operative upon a predetermined departure of the valve towards closed position from its corresponding position for effecting complete closing of the valve and for preventing reopening thereof until the control member is brought to the position corresponding to closed position of the valve.

21. The combination with a valve, of means for operating the same comprising a cylinder, a piston therein and connected to the valve, means biasing the valve to closed position, a control member movable to various positions corresponding to open, closed and intermediate positions of the valve, means responsive to movement of the control member in opening direction for applying fluid pressure to the piston for moving the valve in opening direction and responsive to movement of the control member in closing direction for releasing the fluid pressure from said piston for moving the valve in closing direction, and means operative upon a predetermined departure of the valve toward closed position from its corresponding position for releasing the fluid pressure from said piston until the control member is brought to the position corresponding to closed position of the valve.

In testimony whereof, I have hereunto subscribed my name this 18th day of April, 1928.

ANTHONY F. SCHWENDNER.
